UNITED STATES PATENT OFFICE.

JACOB HENRY ULLRICK, OF NASHVILLE, TENNESSEE.

STILL.

No. 851,045.

Specification of Letters Patent.

Patented April 23, 1907.

Application filed December 30, 1905. Serial No. 293,954.

To all whom it may concern:

Be it known that I, JACOB HENRY ULLRICK, a citizen of the United States, residing at Nashville, in the county of Davidson and State of Tennessee, have invented a new and useful Still, of which the following is a specification.

The present invention relates more particularly to means for distilling water, though not necessarily limited to this use.

The principal object is to provide a novel structure wherein air is commingled with the steam, so that the flat taste is to a very great degree eliminated from the water of distillation.

Means are also provided for securing the escape of objectionable gases and vapors that may be brought over with the steam to be condensed.

Another and important object is to provide a simple still of a novel nature that is very compact, is easily operated and cared for, and is so constructed that it is automatically supplied with water for condensing purposes and with water to be distilled.

The preferred embodiment of the invention is disclosed in the accompanying drawings, wherein—

Figure 1 is a vertical sectional view through the still. Fig. 2 is a top plan view of the same, the condenser-tank being shown in section. Fig. 3 is a vertical sectional view through the filter-tank. Fig. 4 is a top plan view of said tank with the cover removed. Fig. 5 is a vertical sectional view taken substantially on the line 5 5 of Fig. 2 and on an enlarged scale. Fig. 6 is a similar view on the line 6 6 of Fig. 2.

Like numerals of reference designate corresponding parts in all the figures of the drawings.

In the embodiment illustrated a steam-generator 7 is provided, said generator comprising a body 8 and a conical cover 9, the latter having depending flanges 10, that embrace the upper edges of the body-walls, said cover being held in place by suitable clips 11. A cover or casing 12 of asbestos or other suitable material preferably incloses the generator and is spaced from the walls thereof, as shown in Fig. 1. Any suitable heater—as, for instance, a gas-burner 13—may be employed for heating the said generator. A condenser 14 is also provided, said condenser

comprising a closed tank 15, within which is located a coil 16. This tank has an upper offset portion 17, through which extends an inlet-conduit 18, connected to the upper end of the coil 16. The conduit 18 also has communication with an offset discharge-nozzle 19, forming a part of the generator-cover 9. The coil 16 consists of a plurality of whirls, any number of which may be employed, as desired, depending, of course, on the size of the still. This coil is made up of straight angularly-disposed sections 20, each section consisting of angularly-disposed substantially flat walls. The said coil terminates at its lower end in a delivery-spout 21, that projects from the bottom of the condensing-tank 15 and is arranged to receive beneath it a receptacle 22 for the water of distillation. For the purpose of introducing fresh air into the steam and condensed water in the coil an upright air-inlet conduit 23 is provided depending below the tank 15, and preferably having a flared inlet end 24. This conduit extends within the coil transversely of the same and has communication with the different whirls through openings 25. The conduit preferably terminates at the upper end of the coil. Outlets for gas and other objectionable vapors are also provided, said outlets consisting of upright conduits 26, extending transversely of the coil and along the outer side thereof at different points. These conduits have communication with the whirls of the coil through openings 27, and it will be observed that the openings 27 are at different points from the openings 25. As many of said outlets may be employed as desired, the same being preferably controlled by suitable slide valves or gates 28.

Water is supplied to the condensing-tank from any suitable source through a pipe 29, which communicates with the lower portion of said tank and may be closed or regulated by a valve 30. A waste-pipe 31 communicates with the upper portion of the tank, and connected to this waste-pipe is a draw-off pipe 32, having communication with the lower portion of the steam-generator and with the lower portion of the condensing-tank, as shown at 33. Valves 34 and 35 control the flow of water through said pipe 32. The water to be distilled is supplied from the upper portion of the condenser-tank by means of suitable connections. In the pres-

ent embodiment an intermediate filter-tank 36, having a removable cover 35^a, is provided, having an upright slidably-removable filtering-partition 37 therein. This partition, as clearly shown in Figs. 3 and 4, is slidably fitted in guideways formed by sets of spaced angle-irons 36^a, secured to the opposite side walls of the tank 36. Pipes 38 connect the offset portions 17 of the condenser-tank with the filter-tank on one side of the partition, and another pipe 39 connects said filter-tank on the opposite side of the partition with the steam-generator. The supply of water to the generator is automatically controlled in any suitable manner—as, for instance, by means of a float 40, mounted on a pivoted arm 41, which carries an up-standing valve 42, that moves into and out of coaction with the discharge end of the pipe 39 as the float rises and falls.

The operation of the apparatus may be briefly described as follows: The water in the generator being boiled, the steam therefrom will pass through the conduit 18 into the coil 16, wherein it will be condensed and will finally escape through the spout 21 into the receptacle 22. The said condenser-tank is of course filled with water, as is also the filtering-tank 36. Therefore as the level of the water in the generator falls water will be automatically supplied thereto, and this water will be cleared from all sediment by the filtering-partition, which may be readily removed for cleaning purposes. The rapid passage of steam into the coil will cause an indraft through the conduit 23, so that the fresh air will be commingled with the steam and with the water of condensation. This draft can of course have an outlet, and this outlet or escape will be through the conduits 26, so that all odors and objectionable gases will be driven off. To remove the sediment from the generator and condenser-tank, it is only necessary to open the valves 34 and 35, whereupon the water will flow freely into the waste-pipe and fresh water at the same time will be supplied to the tanks. It will be apparent that this structure is exceedingly simple, and it has proved entirely effective for the purpose described.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a still, the combination with a condenser including a coil, of an outlet-conduit

having inlets thereto in communication with different whirls of the coil and having an open discharge end separate from the coil.

2. In a still, the combination with a condenser including a tank and a coil therein, of a substantially upright outlet-conduit extending across the whirls of the coil and communicating therewith, said conduit having an open upper end.

3. In a still, the combination with a condenser including a tank and a coil therein, of an outlet-conduit extending within the tank and located within the coil, said conduit having communication with the inner sides of whirls thereof, and having an open upper end.

4. In a still, the combination with a condenser including a coil, of common means for conducting gases from different whirls of the coil, said means extending across the whirls and having separate communication with each whirl.

5. In a still, the combination with a condenser including a coil, of an outlet-conduit for permitting the escape of gases and the like from the coil, said conduit having a plurality of openings in communication with different whirls of the coil.

6. In a still, the combination with a condenser, comprising a tank, and a coil located therein, of an upright conduit extending through the tank and opening above the same, said conduit extending transversely of the coil and having communication with the different whirls thereof.

7. In a still, the combination with a condenser including a coil, of an air-inlet communicating with different whirls of the coil, and a gas-outlet communicating with different whirls of the coil at different points from the air-inlet.

8. In a still, the combination with a condenser comprising a water-tank and a coil located in the tank, of an air-inlet pipe extending from the exterior of the tank into the same and communicating with one side of the coil between the ends thereof, and a gas-outlet pipe communicating with the opposite side of the coil between the ends of said coil, said outlet-pipe having its discharge end projecting from the tank.

9. In a still, the combination with a condenser including a coil, of an upright air-conduit extending across the coil and having communication with different whirls thereof, and a gas-outlet conduit extending across the coil and having communication with different whirls thereof, and at different points from the inlet communication.

10. In a still, the combination with a condenser-tank, of a coil located therein, and comprising angularly-disposed straight sections, upright inlet and outlet conduits having communication with different whirls of the coil, and extending transversely of certain of the flat sides thereof, means for sup-

plying water to the tank, a generator, a connection between the generator and condenser-coil, and supply means for the generator connected to the condenser-tank.

- 5 11. In a still, the combination with a steam-generator, of a condenser comprising a tank and a coil located in the tank, a steam-conduit connecting the generator and coil of the condenser, an intermediate tank, a de-
10 tachable filter-partition vertically slidable in an intermediate portion of the intermediate tank, a liquid-conducting pipe connecting the upper portions of the condenser-tank and intermediate tank and connected to the latter
15 on one side of the filter-partition, another liquid-conducting pipe connected to the intermediate tank on the opposite side of the partition and connected to the steam-generator,

and means for controlling the passage of liquid from the condenser-tank through the intermediate tank and partition to the generator. 20

12. In a still, the combination with a tank, of a condensing-coil therein, an air-inlet conduit having an inlet end outside the tank, said air-inlet conduit communicating with different whirls of the coil within the tank, and an outlet-conduit having a discharge end outside the tank, said outlet communicating with different whirls of the coil within the tank. 25

In testimony that I claim the foregoing as 30 my own I have hereto affixed my signature in the presence of two witnesses.

JACOB HENRY ULLRICK.
